UNITED STATES PATENT OFFICE.

LOUIS HUDGIN, OF NOGALES, ARIZONA TERRITORY.

DESIGN FOR A GAME-BOARD.

No. 38,303.

Specification for Design.

Patented Oct. 30, 1906.

Application filed September 6, 1905. Serial No. 277,267. Term of patent 3½ years.

To all whom it may concern:

Be it known that I, LOUIS HUDGIN, a subject of the King of Great Britain, residing at Nogales, in the county of Santa Cruz and Territory of Arizona, have invented a new, original, and ornamental Design for a Game-Board, reference being had to the accompanying drawing.

The figure is a plan view of a game-board, showing my new design.

I claim—

The ornamental design for a game-board as shown.

LOUIS HUDGIN.
